UNITED STATES PATENT OFFICE.

ROBERT E. LINDSEY, OF SONORA, CALIFORNIA.

DESIGN FOR A JARDINIÈRE OR SIMILAR ARTICLE.

Application filed August 23, 1927. Serial No. 23,186. Term of patent 7 years.

To all whom it may concern:

Be it known that I, ROBERT E. LINDSEY, a citizen of the United States, residing at Sonora, in the county of Tuolumne and State of California, have invented a new, original, and ornamental Design for a Jardinière or Similar Article, of which the following is a specification, reference being had to the accompanying drawing, forming part thereof, and which is a perspective view of a jardinière showing my new design.

I claim:—

The ornamental design for a jardinière or similar article as shown.

ROBERT E. LINDSEY.
